MOLDS FOR SWING LEG ANCHORS

John Dale Pafenberg, 5714 Birch Ave., McLean, Va.

Filed Nov. 28, 1962, Ser. No. 240,672

1 Claim. (Cl. 25—118)

This invention relates to molds for swing leg anchor members.

Children's yard swing sets are enjoying commercial popularity, and provide an inexpensive recreational outlet for the energies of children that is useful in promoting their physical well-being. A typical swing set is purchased in knocked-down form and assembled at home for use in the yard. The framework is generally of hollow pipe construction, and is made up a main horizontal member supported at its ends by pairs of diverging leg members. When swings are attached to the main horizontal member, the stability of the device is dependent upon the degree of divergence of the supporting legs. If the legs of each pair are widely spaced at their bottoms, then the entire structure is more stable and less likely to rock or move about when the swings are used. The small pipe members generally used in such constructions, together with the weight of the children and their vigorous activities, cause the ends of the legs to become embedded in the ground and tear up the lawn surface. Also, the entire structure tends to change its position because of the rocking motion produced in swinging.

In permanent installations, such as school yards and the like, the problems mentioned above are solved by embedding the ends of the leg members securely in the ground so that the structure cannot move. This usually involves the digging of large holes in which the legs are placed, often attached to buried weights, and, when the job is finished the swings may not be moved about or taken down. In accordance with the present invention the desirable attributes of the knocked-down and permanent type swing sets are combined in a structure that has the disadvantages of neither.

A feature of the present invention is the provision of a mold form which permits the easy application of anchor weights to swing leg members.

Another feature of this invention is the provision of an inexpensive mold form for attaching anchor weights by the ultimate user of a swing set, thereby avoiding the inconvenience and expense of storing and transporting anchor weights prior to use.

A further feature of the invention is the provision of a mold for attaching anchor weights to swing leg members which is incorporated permanently in the anchor weight and provides a decorative outer covering.

Still another feature is the provision of a form for anchor weights for swing leg members which is attached to the leg member and requires only the insertion of pre-formed weights to complete the structure.

A further feature of the invention is the provision of a removable mold form for swing leg anchor weights which is easily detached and re-used.

A still further feature of the invention is the provision of a mold form which is disposable and easily discarded after use.

The principles of the invention may be utilized in various forms, but in accordance with a preferred embodiment of the invention a disposable paper mold form is provided. The form comprises a waterproof paper member shaped as a frustum of a cone. This conical member, which is open at the top and bottom, is placed around the lower portion of a swing leg member. The size of the conical member is chosen in accordance with the volume of material to be placed within the member to determine ultimately the weight anchoring each swing

2

leg. Top and bottom elements are centered on the swing leg member and secure the conical section between them to form a container for the material used as a weight. Preferably, the container serves as a mold for the pouring of concrete, which may be colored suitably, to form a permanently attached weight on each swing leg. The conical wall member is provided with an integral tear strip member to allow the removal of the form after the concrete has hardened.

The foregoing and other objects, features and advantages of the invention will be apparent from the following more particular description of the invention, as illustrated in the accompanying drawings, in which:

FIG. 1 is a perspective view of a swing set utilizing leg anchor members constructed in accordance with the invention;

FIGS. 2a and 2b are perspective and top views, respectively, of a swing leg member showing the means for providing reinforcement for the concrete anchor;

FIG. 3 is a perspective view of a first embodiment of a mold form constructed in accordance with the invention and located about a swing leg member;

FIG. 4 is a perspective view showing a second embodiment of a mold form constructed in accordance with the invention;

FIG. 5 is a perspective view showing another embodiment of a mold form constructed in accordance with the invention;

FIG. 6 is a perspective view showing still another embodiment of a mold form utilizing the features of the present invention; and

FIG. 7 is a perspective view showing a still further embodiment of the invention.

The invention will be understood more readily by making reference to the drawings in which FIG. 1 shows a typical yard swing set to which the principles of the invention have been applied. The swing set comprises a main horizontal member 1 supported at its ends by pairs of diverging leg members 3, 5, 7 and 9. Swings 11 and 13 are suitably suspended from the horizontal member 1. On the bottom portions of legs 3, 5, 7 and 9 are disposed anchor members 15, 17, 19 and 21, respectively.

FIGS. 2a and 2b show in detail how the anchor members 15, 17, 19 and 21 are secured to the swing legs 3, 5, 7 and 9. The swing leg members are provided with holes through which are mounted conventional nails or spikes 23 and 25. The nails 23 and 25 extend entirely through the swing leg member 3 and wires 27 and 29 are passed around swing leg member 3 and attached to each end of the nails 23 and 25. This arrangement provides a means for reinforcing the concrete anchor weight as it is molded about the swing leg member. The arrangement also insures that the anchor member is firmly attached to the swing leg member. While other means of reinforcing are within the scope of the invention, the present arrangement is illustrated as the preferred embodiment because of its simplicity and the availability of materials.

The anchor weights of the present invention may be applied by one of several mold form constructions. FIG. 3 shows a body member 31 shaped as the frustum of a cone and surrounding a swing leg member 30. Although body member 31 could be of cylindrical form, the conical shape is particularly desirable because of the large bottom area for a given volume. A cap member 33 forms a snug sliding fit with swing leg member 30 and is placed over the top of conical member 31. A base member 35 is provided with a cut-out portion 37 to receive swing leg member 30. Base member 35 has a plurality of tabs 38 to 43 formed of cut-out portions which are spaced to receive the bottom edge of conical member 31. When an anchor member is to be molded, conical member 31

is fitted in position and held by tabs 38 to 41 at the bottom portion of swing leg member 30. Concrete is poured in the upper end of conical member 31 until the member is completely filled and there is slight excess left at the top to fill the cap member when it is applied. Cap member 33 is pushed down into position, and any excess concrete is squeezed out. When the concrete is hardened, the anchor member is securely attached to the swing leg member 30. Prior to the pouring of concrete, it is assumed that the swing leg member 30 has been prepared in a fashion similar to that shown in FIGS. 2a and 2b to provide re-enforcement for the concrete and insure that the anchor member is securely attached to the swing leg member.

Conical member 31 shown in FIG. 3, together with cap member 33, are made of suitable plastic materials, and may be provided with any desired decorative effect. In the embodiment of FIG. 3 the members 31 and 33 are designed to become a permanent part of swing leg member 30 and are not removed after the concrete has hardened. Base member 35 is easily removed and discarded.

FIG. 4 illustrates a mold form constructed in accordance with the invention in which the parts are removable and re-usable. In this arrangement the swing leg member 45 is surrounded by conical body member 47 and cap member 49, which are split along their axes and fastened together by means of fasteners 51, 53 and 55. The members 47 and 49 are preferably constructed of sheet metal, and cooperate with a base member 57 which may be of any desired material. When the concrete has been poured and has hardened, the body member 47 and the cap member 49 may be removed by simply loosening the fastener members and lifting the sheet metal forms from around the hardened concrete. In an arrangement such as this, since the concrete is exposed in the final structure, it is often desirable to use a coloring mixture in the concrete to present a decorative effect in the final product. With the arrangement of FIG. 4 it is only necessary to use one form, since the form is re-usable and may be applied to each of the swing legs in turn.

FIG. 5 illustrates a disposable mold form constructed in accordance with the principles of the invention. A swing leg member is shown with a conical member 61 mounted thereon. Cap member 63 and base member 73 are provided and perform functions similar to their corresponding parts described in the previous embodiments. In this arrangement, however, the device is constructed of waterproof paper or fibrous material and the conical body 61 is provided with a tear strip 65 having a pull tab 67 attached thereto. The cap member 63 is provided with a tear strip 69 having a pull tab 71 attached. The base member 73 is provided with attaching tabs 74 to 79 which are coated with a pressure-sensitive adhesive to allow the easy application to conical body member 61, thereby holding base member 73 in secure relationship with the conical member 61. After the concrete has been poured and has hardened, the members 61 and 63 may be removed easily by ripping out tear strips 65 and 69.

The pressure sensitive adhesive tabs 74 and 79 are also easily removed from the conical member 61 to remove the base member 73.

In the embodiment of FIG. 6 the mold form shown is designed to be attached permanently to the swing leg member. The mold form is constructed of sheet metal material and comprises a conical body member 83, cap member 85 and base member 91 disposed about swing leg member 81. The cap member 85 has an upper flange portion 87 provided with a hole 89. The hole 89 permits cap member 85 to be locked in position on swing leg member 81, which is provided with a corresponding hole, by the use of an insertable pin member (shown at 90). The base member 91 has an outer upturned flange portion 93 and an inner circular flange 95 closely surrounding swing leg member 81. The inner flange 95 has a hole 97 provided for locking the base member 91 in place on

swing leg member 81 similar to the locking provision of cap member 83. While the structure of FIG. 6 would be suitable for permanent attachment using poured concrete similar to the embodiments previously described, this arrangement is designed primarily for use with pre-formed weight materials which may be assembled around swing leg member 81 prior to applying conical body member 83. This arrangement also lends itself to the use of dry sand, gravel, or packed earth as a weight material. Although the structure is designed for permanent attachment to swing leg member 81, it is obvious that, since concrete is not cast into the structure, the insertable pins (90 and 98) may be removed at any time and the structure disassembled.

FIG. 7 illustrates an embodiment of the invention in which a unitary plastic sheath 101 of conical shape encases the lower portion of leg member 103. A hole 105 in the top of the sheath 101 allows the leg 103 to be inserted. The hole 105 is keyhole shaped, and portion 107 permits concrete to be poured into the interior of sheath 101. After the concrete has hardened, the mold may be removed or left as an integral part of the structure, as desired. If the sheath is to become an integral part of the structure, appropriate decorative and coloring effects may be incorporated in the plastic.

It is seen from the foregoing description that the present invention provides an easily applied means for efficiently anchoring yard swing sets. The swing legs are held securely in place when the swing is in use, yet the swing set remains portable and may be removed to a new location with a minimum of effort. The use of swing leg anchors prevents lawn wear in one spot as is typical with permanently installed swings and facilitates lawn mowing, since the swings may be moved easily. The large bottom area provided by the conically-shaped weights prevents the swing legs from digging into the ground and the swing is held in proper operating position. The swing life is extended since the strains and tensions introduced into the structure by having one or more legs sink into the ground is no longer present. The use of protruding metal clamps, bolts, sticks and chains often utilized as mechanical anchoring devices is eliminated and thereby reducing the accident hazards. The ease and economy of application allows the present invention to be used by even the most unskilled of handymen. Use of the present invention efficiently anchors the yard swing sets when soil conditions are unfavorable for the use of mechanical anchoring devices or buried weights, e.g. stakes easily pull out of soil having a high sand or gravel content, and rocky or other impervious soils hamper the burying of weights.

While the invention has been shown and described with particular reference to the preferred embodiments, it will be understood by those skilled in the art that various changes in form and details may be made without departing from the spirit and scope of the invention.

What is claimed is:

A mold form for attaching anchoring weights to the leg members of children's yard swing sets comprising a unitary hollow body member of frusto-conical shape for surrounding a swing leg, a frusto-conical cap member with upper and lower flange portions, the upper end of said body member fitting securely within the lower flange portion of said cap member and the upper flange portion of said cap member being shaped for surrounding the swing leg and being provided with a hole for securing said cap member to the swing leg by the insertion of a pin through the hole in the cap member and a corresponding hole in the swing leg, and a base member having a pair of upturned inner and outer concentric flanges, said outer flange being shaped to receive the lower end of said body member and said inner flange having a hole therein and being shaped for surrounding the swing leg to permit the insertion of a pin through the hole in said inner flange and a corresponding hole in the swing leg, whereby said structure forms a container for a suitable weight material used

as an anchoring weight for the swing leg and providing an enlarged base portion to permit the swing leg to rest upon the surface of a lawn without digging in and marring the surface.
